UNITED STATES PATENT OFFICE.

GREEN R. FLOYD, OF BENSON, ALABAMA.

TOY.

1,357,159.

Specification of Letters Patent. Patented Oct. 26, 1920.

Application filed January 31, 1920. Serial No. 355,493.

To all whom it may concern:

Be it known that I, GREEN R. FLOYD, a citizen of the United States, residing at Benson, in the county of Tallapoosa and State of Alabama, have invented new and useful Improvements in Toys, of which the following is a specification.

This invention relates to amusement devices, particularly to toys, and has for its ob-

ject the provision of a toy which includes a plurality of rotatable members carrying whistles having different notes or pitches which will be sounded by the draft of air caused by their rotation, the device further including a platform and a plurality of dolls suspended immediately above the platform and moved by pitmen whereby to have the effect of dancing, other dolls being seated upon benches at the sides of the plat-
form to give the appearance of an audience.

An important object is the provision of an amusement device of this character which is provided with other dolls holding miniature imitation instruments, such as banjos or guitars, the right arms of these dolls being connected with the pitmen whereby during movement thereof the dolls will have the appearance of playing upon the instruments and furnishing music for the dancing dolls, though the music is actually furnished by the rotating whistles.

An additional object is the provision of a toy of this character which will be comparatively simple and inexpensive in manufacture, very amusing in use, effective in operation, and a general improvement in the art.

With the above and other objects and advantages in view, the invention consists in the details of construction to be hereinafter more fully described and claimed, and illustrated in the accompanying drawings in which—

Figure 1 is a side elevation of my device, Fig. 2 is a longitudinal sectional view, Fig. 3 is a plan view,

Fig. 4 is an elevation, taken at right angles to Fig. 1,

Fig. 5 is a sectional view taken at right angles to Fig. 2,

Fig. 6 is a horizontal sectional view looking down upon the platform.

Referring more particularly to the drawings, I have shown my device as comprising a supporting base or platform 10, from the corners of which rise uprights 11 which

carry at their upper ends an elevated platform 12 which is provided centrally with a circular hole 13. Secured between the uprights 11 at opposite sides of the device, are benches 14 upon which are seated dolls 15, possibly of different sizes and probably of different shapes and colors, and it is of course apparent that these dolls should have a smiling expression.

Secured upon the base 10 are pairs of upwardly converging supports 16 which terminate within the hole 13 and journaled above the upper ends of these supports is a shaft 17 mounted within suitable bearings 18 mounted upon the platform 12. Also journaled between the supports 16 are other shafts 19 which are connected with each other and with the shaft 17 by means of a suitable flexible member or belt 20 which is engaged about flanged pulleys 21 on the different shafts. The shaft 17 is preferably elongated and carries a crank handle 22 whereby all the shafts may be rotated, though it will be apparent that if desired, a spring motor or an electric motor, not shown, might equally well be utilized for rotating the various shafts.

Secured upon each of the shafts 17 and 19 are plates 23, each of which is provided in its opposite ends with a pair of holes 24 within which are engaged wind whistles 25 having flaring or funnel-shaped entrances 26. These whistles must of course be delicate in construction so that they will be sounded by the draft or wind caused by rotation of the shafts. Another feature is that these various whistles are of different notes or pitches so that a more or less siren-like effect will be produced when they are in operation.

Extending between the base and elevated platforms 10 and 12, respectively, are upright wire members 27 which are formed intermediate their ends with loops 28. The shafts 19 have secured at or near their diagonal opposite ends disks 29 which have eccentrically connected therewith pitmen 30 which have their other ends slidably through the loops 28. Secured upon each pitman is a plurality of jointed dolls 31 which are of course lightly constructed and which are so arranged that when the pitmen are at their lowest points the feet of the dolls will engage the base platform 10 so as to produce the effect of dancing and it will be apparent that as the pitmen move the dolls will be

considerably shaken about so as to display lively and incessant movement.

Disposed upon the benches 14 at diagonally opposite corners of the base platform 5 are other dolls 32 which are the representations of musicians and these dolls carry miniature instruments which may be banjos, guitars, or the like. Each of these last mentioned dolls has one arm pivoted so that it 10 may be moved to give the appearance that the doll is playing the instrument and these pivoted arms 34 are connected with the pitmen 30 by links 35.

In the operation of the device it will be 15 seen that when the operator rotates the crank handle or turns the shaft 17 by any other desired means, the shafts 19 will be rotated, the pitmen 30 will be moved to impart to the dolls suspended therefrom a dancing movement and the musician dolls will go through 20 the motions of playing their instruments. At the same time the whistles carried by the various shafts will be playing in different pitches and it will consequently be apparent 25 that the device will be highly amusing and entertaining, especially to the young.

While I have shown and described the preferred embodiment of my invention, it is of course to be understood that I reserve 30 the right to make such changes in the form, construction, and arrangement of parts as will not depart from the spirit of the invention or the scope of the subjoined claims.

Having thus described my invention, 1 35 claim:

1. A device of the character described comprising a base platform, a plurality of supports rising therefrom, transverse shafts journaled through said supports and connected for simultaneous movement, means for moving said shafts, a plate member carried by each shaft and having its opposite ends provided with holes, and whistles mounted in said holes and having funnel 40 entrances.

2. A device of the character described comprising a base platform, a plurality of uprights rising therefrom, an elevated platform carried by the uprights and provided with a 50 central hole, a shaft journaled upon said elevated platform and extending across the hole, upwardly converging supports carried by the base platform and extending into said holes, shafts journaled through said supports 55 and connected with each other, and with said

first named shaft whereby all of said shafts will rotate simultaneously, means for rotating said shafts, a plate carried by each shaft and having its opposite ends provided with holes, and a wind operated whistle mounted 60 in each hole and having an elongated flaring entrance.

3. A device of the character described comprising a base platform, a plurality of uprights rising therefrom, an elevated platform carried by the uprights and provided with a central hole, a shaft journaled upon said elevated platform and extending across the hole, upwardly converging supports carried 65 by the base platform and extending into said hole, shafts journaled through said supports and connected with each other and with said first named shaft whereby all of said shafts will rotate simultaneously, means for rotating said shaft, a plate carried by each shaft 70 and having its opposite ends provided with holes, and a wind operated whistle mounted in each hole and having an elongated flaring entrance, in combination with movable members 75 operated by rotation of said second named shafts and carrying a plurality of jointed dolls.

4. A device of the character described comprising a supporting platform, supports rising therefrom, shafts journaled through said 80 supports and connected for simultaneous movement, means for rotating said shafts, an upright guide member at each side of the platform, a pitman eccentrically connected 85 with each of said shafts and slidably engaged with said guide members, and a plurality of jointed dolls mounted on each pitman.

5. A device of the character described comprising a supporting platform, supports rising therefrom, shafts journaled through said 90 supports and connected for simultaneous movement, means for rotating said shafts, an upright guide member at each side of the platform, a pitman eccentrically connected 95 with each of said shafts and slidably engaged with said guide members, and a plurality of jointed dolls mounted on each pitman, in combination with a doll figure disposed at diagonally opposite corners of the 100 platform and having one arm pivoted, and links connected with the pivoted arms of said last named dolls and with said pitmen.

In testimony whereof I affix my signature.
GREEN R. FLOYD.
